UNITED STATES PATENT OFFICE.

ALBERT JAMES ROSCOE, OF NEW BEDFORD, MASSACHUSETTS, ASSIGNOR TO
THE PAIRPOINT MANUFACTURING COMPANY, OF SAME PLACE.

DESIGN FOR A BOX.

SPECIFICATION forming part of Design No. 23,191, dated April 10, 1894.

Application filed February 15, 1894. Serial No. 500,310. Term of patent 3½ years.

To all whom it may concern:

Be it known that I, ALBERT JAMES ROSCOE, of New Bedford, in the county of Bristol and State of Massachusetts, have invented and 5 produced a new and original Design for a Round Box, of which the following is a specification, reference being had to the accompanying drawing.

The leading feature of my design is a box side having downwardly turned projecting ears, and upon its exterior surface a band formed into a bow beneath the downwardly turned ears.

In the drawing, *a* is the bottom and *a'* the

box-side which rises from the bottom *a* and 15 has triangular ears *a*², which project downwardly and form a V-shaped recess in the upper edge of the box-side, and *b* is a cover. Around the exterior of the box-side *a'* is a band which is formed into the shape of a bow 20 *d* beneath the ears *a*², and *d* is a box knob.

I claim—

The design for a box herein shown and described.

ALBERT JAMES ROSCOE.
